UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

COOK STOVE.

Application filed July 8, 1927. Serial No. 204,163.

The invention pertains generally to cook stoves or ranges and more particularly to a cooking top of a novel and advantageous character.

5 The primary object of the invention is to provide a new and improved cooking top for liquid and gaseous fuel stoves, adapted to provide a smooth completely closed top when desired, and having one or more openings therein closed by a removable cover plate with means for supporting utensils of varying sizes over the opening when the cover plate is removed.

Another object of the invention is to provide a novel means for closing the burner openings in the top.

Still another object is to provide a cooking top whereby high heating efficiency is attained.

20 Other objects and advantages will become apparent from the following descriptions and in the accompanying drawings in which:

Figure 1 is a perspective view of a gas stove embodying the invention.

Fig. 2 is a plan view of the preferred form of the invention.

Fig. 3 is a plan view of a closure for one of the cooking apertures.

30 Figs. 4 and 5 are sectional views on the lines 4-4 and 5-5 respectively, of Fig. 2 looking in the direction of the arrows.

In the embodiment selected and shown herein for the purpose of illustration, the 35 invention is incorporated in a gas range of customary construction having a body 6 supported on suitable legs 7. The body has at one side an oven section comprising a broiler compartment 8 and a superimposed oven compartment 9 and at the other side a cooking top 10 with a burner chamber formed beneath it and containing a plurality of suitable burners (not shown). A flue connection 12 may be provided in the usual 45 manner to conduct away the waste gases from the burner chamber and the oven section. The essential features of the invention primarily reside in the construction of the cooking top 10.

50 In the ordinary construction the cooking top comprises an open grid-work forming a number of spiders which are mounted over the burners. Obviously in such a construction a large amount of heat escapes through 55 the open grid, thus lowering the heating

efficiency of the stove. In attaining the objects of this invention a thin flat closed cooking top has been provided having a number of burner openings therein. Utensil supporting spiders are provided for one or 60 more of the burner openings, and such spiders are arranged to permit means for completely closing the opening to be received in the cooking top in such manner that the upper and lower surfaces of the 65 closure will be flush with the upper and lower surfaces of the plate.

In the present embodiment the stove is provided with a frame 13 having a central opening which is positioned over the burners. The edges of the frame about the opening are rabbeted as shown at 14, Fig. 4, to receive and support the cooking top 10 which preferably comprises a flat level plate of a size and thickness to fit snugly in the 75 rabbeted edges 14 of the frame 13 with the upper surface of the top substantially flush with the upper surface of the frame. Disposed about the cooking top are a plurality of burner openings 15 positioned so that 80 when the top is mounted in the stove, an opening will be immediately above each of the burners. The burner openings are provided with a plurality of inwardly extending radial ribs 16 which form a utensil supporting spider. As may be seen in Fig. 5, the ribs are trapezoidal in cross section, the upper part of the rib being the narrower part of the trapezoid. Intermediate each 85 rib, the edge of the burner opening is cut away from the upper surface to provide an inwardly extending flange 17. Thus a cooking top is provided in which a plurality of burner openings having utensil supporting spiders therein may, if desired, be integrally 90 formed from cast metal.

It is frequently desirable in this type of cooking top to close one or more of the burner openings, either for the purpose of confining the heat to one opening or for 100 providing a warming plate in which a utensil may be warmed without coming in contact with an open flame. To this end a closure plate or lid 18 is provided for each burner opening which is arranged to fit in the opening in such manner that the upper and lower surfaces of the closure are level with the upper and lower surfaces of the cooking top. The plate 18, as shown in Fig. 3, is arranged to fit relatively snugly with- 105 110

in the burner opening 15, and is provided with a plurality of radial slots 19 which, when the plate is positioned in the opening, receive the ribs 16. The side edges of the 5 slots are beveled downwardly to provide surfaces complementary to the side surfaces of the ribs. Thus, upon engagement of the ribs 16 with the slots 19, a wedging action therebetween provides a means for supporting the plate in the burner opening. As an 10 additional means of support the peripheral edge of the plate is rabbeted to provide a peripheral flange 20 extending outwardly from the upper surface of the plate, which 15 flange 20 is adapted to engage the flange 17 projecting inwardly of the burner opening when the plate is positioned in the opening. The plate may be suitably apertured, as at 20 21, to receive a means for removing the plate from the top.

By the above described construction a cooking top has been provided which is capable of being entirely closed, by means of the snugly fitting closure plates, to provide a 25 warming top, upon which utensils may be warmed or slowly heated out of direct contact with the flame. Moreover, one or more of the burner openings may be opened to permit a utensil to be heated directly by the 30 burner. Since the spider permits the utensil to rest thereon flush with the surface of the top, that burner opening will be partially or entirely closed thereby and in either 35 event the remaining portions of the top will be heated by the hot gases deflected thereacross by the utensil.

Means has been provided in the present 40 instance for insuring a more complete and efficient heating of the more remote portions of the cooking top from any of the burners. Since this heating is done almost entirely by the passing of the hot gases from the burner along the under surface of the cooking top it becomes essential that there be no 45 projections thereon which would tend to obstruct the free flow of the heated gas.

In order to provide a greater heating surface on the lower surface of the plate, a 50 large number of small pointed studs 22 are provided thereon. The studs 22 are formed or cast integrally with the top 10 and greatly increase the heating surface over which

the heated gases flow without materially hindering the free passage of the gases. It will be seen therefore, since the surface to 55 be heated is so great, and the cooking top is relatively thin, that substantially all of the heat from the gases will be absorbed by or transferred to the cooking top.

The cooking top as herein disclosed lends 60 itself particularly to a very economical construction since it may be cast in one piece. Moreover, the closures are so formed and mounted in the burner openings that no part projects or extends below the plane of the 65 lower surface, which permits a free passage of the gases therebeneath and allows the spent gases to pass to the flue connection without hinderance.

Although the invention is susceptible of 70 various modifications and alternative constructions, I have shown and herein described in detail the preferred embodiment but it is to be understood that I do not thereby intend to limit the invention to the 75 specific form disclosed but intend to cover all modifications and alternative constructions falling within the spirit and scope of the invention as expressed in the appended claim.

I claim as my invention:

A stove top comprising, in combination, a plate having a circular burner opening therein, a plurality of ribs formed integral with the plate and extending radially into said 80 opening, said ribs being equidistantly spaced apart and terminating short of the axial center of the opening, and a cover plate for said opening having a plurality of radially disposed slots having their outer ends 85 terminating in the periphery of the cover plate, said cover plate being adapted to fit into said opening with its upper surface flush with the upper surface of the top plate and with said ribs entered in said slots, 90 said ribs and slots being of greater width at their lower edges than at their upper edges whereby the ribs are adapted to engage and support the plate throughout the length of the ribs.

In testimony whereof, I have hereunto affixed my signature.

GEORGE E. PICKUP.
